UNITED STATES PATENT OFFICE.

PETER CHRISTENSEN, OF KINGSVILLE, TEXAS.

SWINGING CRADLE.

1,133,429.

Specification of Letters Patent. Patented Mar. 30, 1915.

Application filed May 1, 1913. Serial No. 764,855.

To all whom it may concern:

Be it known that I, PETER CHRISTENSEN, a citizen of the United States of America, residing at Kingsville, in the county of Nueces and State of Texas, have invented certain new and useful Improvements in Swinging Cradles, of which the following is a specification, reference being had therein to the accompanying drawing.

10 This invention relates to an improved type of baby crib which is so constructed that it may be removably connected with one of the side posts of a bed.

The principal object of this invention is 15 the production of a horizontal crane which is so formed as to allow a link to be carried thereon, which is provided with simple and efficient means for preventing the accidental displacement of the link.

20 Another object of this invention is to provide an improved link for connecting the crib with the crane.

With these and other objects in view, this 25 invention consists of certain novel constructions, combinations and arrangements of parts, as will be hereinafter fully described and claimed.

This invention is illustrated in the accompanying drawings, wherein:—

30 Figure 1 is a side elevation showing the crib swung to the rear of the bed and indicated in dotted lines in the reverse position. Fig. 2 is a vertical sectional view through the crib and the upper portion of 35 the bed post. Fig. 3 is a section taken on the line 3—3 in Fig. 2. Fig. 4 is a side elevation of the lower portion of the crane. Fig. 5 is an enlarged sectional view through the portion of the crane shown in Fig. 4. 40 Fig. 6 is a sectional view through the upper portion of the crane. Fig. 7 is a perspective view of the link which connects the crib with the crane.

Referring to the accompanying drawings, 45 it will be seen that this invention is removably connected with one of the side posts 10 of a bed by the clamps 11 and 12 each of which comprises the two members 13 and 14 held together by the securing bolt 15. 50 It will thus be seen that when it is not desired to use the crib it may be disconnected from the bed and put away thus making it unnecessary at all times to have the crib connected with the bed.

55 The crib comprises the tubular sleeve 16 which is engaged by the clamps 11 and 12

and in which the crane 17 is rotatably mounted. This crane is provided with a collar 18 which is held in an adjusted position by the set screw 19 thus permitting the 60 crane to be vertically adjusted and thus the movement of the crib regulated. The lower end portion of the crane is provided with vertically extending slots forming the tongues 20 and 21 which tongues are bent as 65 shown at 22 to cause the lower end portion of the crane to have a binding engagement with the sleeve 16 when the tongues are forced away from each other by the springs 23 and 24 engaging the tongues 20 and 21 70 respectively. From an inspection of Fig. 2, it will be readily seen that these springs 23 and 24 will force the tongues 20 and 21 into tight engagement with the sleeve and that due to this the crane will remain in an adjusted position when turned in the sleeve 75 thus preventing the crane from swinging out of the position in which it is desired that it should be kept.

A stem 25 is rigidly secured in the upper 80 end of the crane 17 and is provided with a hook-shaped outer end portion 26 having its bridge provided with the cone-shaped bearing 27. A link 28 is provided with an opening 29 through which the bridge of the hook 85 26 passes. This link rests upon the cone-shaped bearing 27 with the bearing fitting in the notch 30 and is prevented from slipping from the bridge by the strip held in place by means of suitable securing screws 90 or bolts 32. Chains 33 are connected with flanges 34 at the lower end of the link 28 and have their lower ends connected with the basket 35. The upper portion of the link is formed into a neck 36 terminating in an 95 eye 37 with which a line 38 may be connected so that if it is desired to swing the crib, the line may be operated to rock the link thus causing the basket to swing back and forth. If it is desired to swing the crib 100 over the bed, the crane may be turned in the sleeve thus turning it from the position shown in Fig. 1 in full lines to that indicated by the dotted lines. It should also be noted that the line 38 may be used as a 105 means for turning the crane thus making it easy to turn the crib to the desired position without it being necessary to leave the bed.

Having thus described the invention, what is claimed as new, is:—

110 1. In a device of the class described the combination with a supporting crane, a stem

carried by the upper outer end of said crane, said stem terminating in a horizontal hook-shaped outer end, a cone-shaped bearing lug formed upon said hook-shaped outer end, a link pivoted upon said cone-shaped bearing lug, said link adapted to support a cradle, and a strip engaging the body portion of said stem and the end portion of said hook-shaped outer end, whereby said link will be held against accidental displacement.

2. In a device of the class described, the combination of a supporting crane, a stem secured to said supporting crane, and terminating in a horizontal hook-shaped outer end, a cone-shaped bearing lug formed upon said hook-shaped outer end, of a link, said link comprising a body having an opening, said body having a notch communicating with said opening, said hook-shaped outer

end of said stem positioned through said opening so as to allow the upper portion of said bearing lug to rest within said notch of said body, said body having an upwardly extending neck terminating in an eye, said eye adapted to carry a cord whereby the link may be rocked upon said bearing lug, and laterally extending flanges formed upon the lower portion of said body whereby securing means may be attached thereto for supporting a cradle, said link being adapted to swing a cradle as the link is being rocked upon said bearing lug.

In testimony whereof I hereunto affix my signature in presence of two witnesses.

PETER CHRISTENSEN.
